CUTTING APPARATUS

Daniel V. Waters, Flemington, N. J., assignor to
 Western Electric Company, Incorporated, New
 York, N. Y., a corporation of New York

Application June 10, 1941, Serial No. 397,361

4 Claims. (Cl. 125—13)

This invention relates to cutting apparatus, and more particularly to an apparatus for cutting quartz crystal plates from a quartz crystal blank.

Quartz crystal plates are used, for example, in filters in the communication arts, and these plates are usually cut by the aid of a diamond edge saw from quartz crystal blanks. Due to the brittle nature, the granular structure and the natural hardness of quartz crystal blanks, the cutting of plates of definite and uniform thickness therefrom is quite difficult and painstaking. The crystal plates cut from the crystal blanks must be cut with the grain of the blank and when the plates are rather thin difficulties arise in avoiding breaking the plates before the cut is completed.

An object of the invention is to provide a cutting apparatus which is particularly adapted for efficiently and accurately cutting plates from quartz crystal blanks.

With this and other objects in view, the invention comprises a cutting apparatus including a work or quartz crystal table for the support thereof which, in addition to being mounted for movement into various angular positions relative to a driven cutting element, is caused to move arcuately through a cutting operation by the element and simultaneously oscillated to cause substantially point contact between the element and the work, means also being provided to shift the support after each cutting cycle to position the work for a new cut.

Other objects and advantages will be apparent from the following detailed description when taken in conjunction with the accompanying drawings, wherein

Fig. 1 is a side elevational view of the apparatus;

Fig. 2 is a top plan view of the apparatus, portions thereof being broken away;

Fig. 3 is a fragmentary sectional view taken substantially along the line 3—3 of Fig. 2;

Fig. 4 is a side elevational view of the apparatus, portions thereof being removed to illustrate the table and oscillating mechanism in the forward position;

Fig. 5 is a side elevational view of the apparatus similar to Fig. 4, showing the table and its oscillating mechanism in its rearmost position;

Fig. 6 is a fragmentary sectional view taken substantially along the line 6—6 of Fig. 2;

Fig. 7 is a fragmentary sectional view taken substantially along the line 7—7 of Fig. 2;

Fig. 8 is a fragmentary detailed view illustrating the relative position of the table and the cutting element at the beginning of a cutting cycle;

Fig. 9 illustrates the relative position of the

work and the cutting element at one end of an oscillatory movement of the work;

Fig. 10 is a fragmentary detailed view illustrating the relative positions of the work and the cutting element at the other end of the oscillatory movement of the work;

Fig. 11 is a sectional view of the work illustrating a completed work;

Fig. 12 is a simple wiring diagram illustrating the electrical as well as the pneumatic control means for the mechanism moving the work supporting table;

Fig. 13 is a diagram illustrating an operating cycle of the apparatus and the points during which various portions of the structure function to automatically carry out the operation of the apparatus; and

Fig. 14 is a fragmentary sectional view taken along the line 14—14 of Fig. 1.

Referring now to the drawings, attention is first directed to Figs. 1 and 2, which illustrate a hollow base 10 mounted upon a suitable support, such as a table 11, and having spaced frames, indicated generally at 12 and 13, mounted thereon by any suitable means (not shown). The frames 12 and 13 are identical in structure excepting that one, the frame 12, might be called a right-hand frame while the other might be called a left-hand frame due to the fact that channel members of which the frames are composed have their open sides facing outwardly. In each frame there are vertical channel members 15 and 16 joined at their lower extremities by interposed channel members 17 lying upon the upper surface of the base 10, while the upper extremities of the channel members 15 and 16 of each frame are joined by a diagonally projecting channel member 18 as illustrated in Fig. 1. Shaft supporting brackets 21 of the contour illustrated in Figs. 1, 3, 4 and 5 project downwardly in the hollow upper portions of their respective vertical members 15 of each frame, where they are secured rigidly by any suitable means such as screws. Similar shaft supporting brackets 22 project downwardly in the hollow portions of their respective vertical frame members 16 and are similarly secured in place. A suitable shaft 23 extends through the brackets 21 and has nuts 24 threadedly disposed upon threaded ends thereof to secure the shaft against displacement. A similar shaft 25 has threaded ends extending through the brackets 22 and are secured in place by nuts 26 disposed on the said threaded ends.

A pair of pendulum levers 28 is mounted on the shaft 23 between the frames 12 and 13 and held in their respective spaced positions by a sleeve 30. In actual structure the pendulum levers 28 are mounted upon roller bearings 31, only one of which is shown and this being illustrated in

Fig. 3. The roller bearings are mounted upon the shaft 23 and held against lateral displacement on one side by washers 32 and on the other side by sleeves 33, the latter abutting against the bearing brackets 21. As illustrated in Fig. 3 and also in Fig. 2, the ends of the sleeve 30 have flanges 34 apertured for screws 35 and 36 to secure the flanges to their respective pendulum lever 28, the screws 36 extending through apertures in the levers and threadedly secured to respective end plates 38, closing the ends of the lever and sleeve assemblies on the shaft 23.

Pendulum levers 40 are mounted upon their shafts 25 by the aid of bearings and with a structure identical with the mounting of the pendulum levers 28, upon their shaft 23 and, as illustrated in Fig. 3, including a roller bearing for each pendulum lever 40, a spacing sleeve 41 (Fig. 2) with flanges 42 at the ends thereof to receive screws (not shown) to secure the flanges 42 to their respective pendulum levers 40 and also to the end plates 43, completing the mounting structure for the pendulum levers 40 identical with that of the pendulum levers 28.

Returning now to the pendulum levers 28, it will be observed that these levers are joined by an intermediate reenforcing member or plate 45. The lower ends of the levers 28 are bent forwardly, providing substantially horizontal portions 47, in the ends of which stub shafts 48 are mounted. The stub shafts 48 assist in supporting rocker arms 50 short of the ends thereof, as illustrated in Fig. 2. These arms extend rearwardly from the stub shafts, are bent inwardly, that is toward each other, at like angles for short distances, as indicated at 51 (Fig. 2), and are then provided with apertured portions 53 lying in parallel planes at right angles to the shafts 23 and 25. The portions 53 of the rocker arms 50 are disposed on bearings similar to the roller bearings 31 in Fig. 3 but not shown, for here again a structure is provided which is identical to the mounting of the pendulum levers 28. This structure includes a shaft 54, similar in structure to the shaft 23, supporting near the ends thereof the bearings upon which the portions 53 of the rocker arms are disposed and provided with a spacing sleeve 55 of like structure to the spacing sleeves 30 and 41, with end flanges 56 apertured to receive screws not shown but similar to the screws 35 and 36 of Fig. 3 to secure the flanges 56 of the spacing sleeve 55 to the portions 53 of the rocker arms 50 and also to end plates 57, closing the ends of this assembly. The outer ends of the shaft 54 project through the lower ends of the pendulum levers 40 and receive nuts 58 and lock washers 59 to secure the pendulum levers against displacement on the shaft 54 yet permit relative movement between the shaft and the pendulum levers.

The forward portions of the rocker arms 50, that is, those portions extending forwardly from the stub shafts 48, support stub shafts 60 which in turn support bearings 61, similar bearings 62 being also provided for the supporting of the stub shafts 48 in the lower ends of the pendulum levers 28. A support 63 has end portions 64 projecting forwardly at right angles therefrom with apertured end portions 65 in which the bearings 61 are mounted, completing the mounting of the support 63 upon the stub shafts 60. In the face of the support 63 an arcuate groove 67 is formed to receive tongue portions 68 of a table supporting member 69 and also tongue-shaped heads 70 and bolts 71 (Figs. 1 and 14), the latter projecting

through an aperture in the table supporting member through a sleeve 72, where it is provided with a wing nut 73 serving to lock the table supporting member in any desired position relative to the support 63.

The table supporting member 69 is of the contour illustrated in Figs. 1 and 2 and has angularly projecting or dovetail portions 75 extending longitudinally thereof and receivable in a dovetail groove 76 (Figs. 1 and 8) of a table 78. The table 78 has a downwardly projecting portion 79 (Fig. 8) with a threaded aperture therethrough to serve as a nut for a traversing screw 80. The table 78 is, therefore, connected to the supporting member 69 through the dovetail portions 75 and the dovetail groove 76, which permit the movement of the table relative to the supporting member 69 by rotation of the traversing screw 80. The upper portion of the table 78 is square in general contour, having a raised circular portion 83 providing a flat surface upon which work 84, which in the present instance is a quartz crystal blank, may be mounted by any suitable means such as cement, indicated at 85 in Fig. 8. The circular portion 83 of the table has a central shank 81 extending through an aperture in the table proper 78 to support the portion 83 for circular adjustment. A hand-operated lock screw 86 carried by the table is positioned to engage the shank 81 to lock the portion 83 in any desired position.

Attention is now directed to the traversing screw 80 and the mechanism for causing rotation thereof. The ends of the traversing screw 80, which are free of threads, are journaled in portions of the table supporting member 69 and provided with suitable means, such as head member 87, to hold the adjusting screw against longitudinal movement. A worm gear 88 (Fig. 7) is mounted upon the traversing screw 80 adjacent one end thereof and interengages a worm 89. The worm 89 is fixedly mounted upon a shaft 90, the latter being journaled in bearings 91 of a housing 92 formed as a part of the table supporting member 69 and covered with a plate 93. The forward end of the shaft 90 (Fig. 2) projects through the housing 92 and has a hand wheel 94 mounted thereon for manual rotation of the shaft and, through the worm and worm gear, manual actuation of the traversing screw 80. The other end of the shaft 90 has a universal joint 96 connecting it with a portion 97 of a telescoping shaft indicated generally at 98. The other portion 99 of the telescoping shaft 98 is tubular in cross-section, permitting axial movement of the shaft portions 97 and 99 relative to each other yet are provided with key or spline connections (not shown) assuring simultaneous rotation one with the other. The shaft portion 99 is connected to a shaft 101 through a universal joint 102. The shaft 101 is journaled in bearings of a base member 104 (Fig. 6), the latter being rigidly mounted upon the spacing sleeve 55. The other or rearward end of the shaft 101 has a gear 105 mounted for free rotation thereon and which interengages a pinion 106 of a motor shaft 107. The shaft 107 is from a motor 108 mounted upon the support 104.

Returning again to the shaft 101, a free wheeling clutch 109 is mounted thereon and formed to cause positive connection between the gear 105 and the shaft 101 when the motor is driven in one direction but to allow the gear 105 to rotate freely on the shaft when the motor is driven in the opposite direction. The clutch 109 is of the

conventional type illustrated in Bulletin #131, March 2, 1937, in a catalog published by the Hilliard Corporation, Elmira, N. Y., entitled "The Hilliard Line Clutches and Couplings." In view of the fact that the clutch 109 is of a well known commercial type, it is believed that a detailed illustration and description of this clutch is not necessary as long as its function is made clear. The function of the clutch, as stated above, is to cause positive connection between the gear 105 and the shaft 101 when the motor is driven in one direction and to allow the gear 105 to rotate freely on the shaft when the motor is driven in the opposite direction.

When the motor 108 is driven in one direction to cause the clutch 109 to function, lateral adjustment of the table 78 is brought about. However, during rotation of the motor 108 in the opposite direction, means is actuated to cause oscillatory movement of the table 78 through similar movement imparted to the support 63. The forward end of the motor 108 has a driving connection with a lateral shaft 112 upon which eccentric 113 is mounted. The driving connection between the motor 108 and the shaft 112 is not shown but this may be composed of suitable gears disposed in the housing of the motor, to cause rotation of the shaft 112 approximately 20 R. P. M. A link 114 (Figs. 1, 2 and 6) has one end connected to the eccentric 113, while the other end, which has a right angle bend therein as shown in Fig. 1, is pivotally connected, at 115, to a bracket 116, the latter being mounted upon the rear wall of the support 63 adjacent the center thereof. Therefore, during rotation of the motor 108, the shaft 112 is rotated with the eccentric 113, imparting movement to the link 114 which, through the bracket 116, will impart an oscillatory movement to the support 63 and the table 78 through the pivotal supporting means for the support 63, namely the stub shafts 60.

Attention is now directed to a cutting element 120 which is rotatably mounted upon a shaft 121 of a motor 122, the latter being supported by bearing brackets 123 connected to the base 10 and formed to house bearings for the shaft 121. The cutting element 120 may be of any suitable structure, which in the present instance is of the type used for cutting stone. A guard 124 is mounted to partially house the cutting element, as shown in Figs. 1 and 2, and a suitable lubricant may be directed through the guard to the cutting element from a supply line 125. It will be understood that the cutting element is disposed at a fixed position and that the work is moved relative thereto.

Description has been given as to how the table 78, supporting the work 84, may be moved laterally to position the work for successive cuts by the cutting element and how the table may be oscillated during such cutting operations. Attention is now directed to one of the means to move the table relative to the cutting element, namely the table return moving means which conditions the table feeding means for actuation. The table return moving means includes an arm 128 integral with one of the pendulum levers 40, the one at the left (Fig. 2), attention also being directed to Figs. 1, 4 and 5, the juncture of the arm 128 with its lever 40 being adjacent the shaft 25. The arm 128 is bent, as illustrated in Fig. 2, to present its outer end to a piston rod 129, a pivoted connection being provided between the arm and the piston rod. The piston rod 129 is connected to a piston 130 (Fig. 12) which is disposed in a cylinder 131, the latter

being pivotally supported at 132 (Figs. 4 and 5) to a bracket 133, the latter being mounted upon the base 10. The cylinder 131 is provided with air under pressure from a supply line 134 through the control of electrically operated valve 135 (Figs. 1 and 12) disposed in the line. When the valve 135 is opened, this taking place at a time when the piston 130 is in its uppermost position, air under pressure will be supplied to the cylinder above the piston to move the piston downwardly at a speed controlled by a needle or pressure relief valve 136. Through this movement of the piston the piston rod 129 will be moved downwardly, imparting movement to the arm 128 to move the pendulum levers 40 (Figs. 1, 4 and 5) forwardly (clockwise) from the position shown in Fig. 5 to the position shown in Fig. 4, this movement imparting motion to the pendulum levers 28 through the rocker arms 50 to move the support 63 together with the table 78 into its starting position, as illustrated in Fig. 4. This constitutes means for imparting a return movement to the table and the work thereon relative to the cutting element 120.

Means is provided to counter-balance the pendulum levers not only in their return movement but in their feeding movement, which will hereinafter be described. The counter-balancing means includes a tension spring 137 which has its lower end connected to a hook 138 fixed to the base 10, the upper end of the spring being connected to an adjustable coupling 139 which connects this end of the spring pivotally, as at 140, to an arm 141. The arm 141 is formed as an integral part of the other pendulum lever 40, that is the one disposed at the right (Fig. 2) and is of the shape illustrated in this figure to position the spring 137 beyond the adjacent frame 12. During the oscillatory movement of the pendulum levers 40, moving the table with the work relative to the cutting element, the pivotal connection of 140 of the arm 141 and the spring 137 are moved from one side of a dead center above the shaft 25, to the other side thereof, to assist in moving the pendulum levers in either direction they are travelling as soon as the pivotal connection 140 passes the dead center point. The spring 137 therefore, functions to counter-balance the pendulum levers, adding its force to the movement of the levers in either direction to bring about a predetermined feeding pressure effective to move the table and its work relative to the cutting element.

Attention is now directed to the means for moving the table and its associated structures in the feeding direction to move the work relative to the cutting element, to cause the cutting element to cut a path through the work. This feeding means includes a spring 144 which provides the force to move the table and its supporting structures in the feeding direction. The spring 144 has one end connected to a bar 145, the latter being adjustably connected to a wall of the base 10, the spring also being partially housed in the base. The other end of the spring is provided with a circular coil 146 through which a rod 147 extends. The rod 147 is threaded and extends through a sleeve 148, where the rod is provided with nuts 149 which cooperate with the rod in providing an adjustment to vary the force of the spring 144. The outer end of the rod 147 is connected to a strip 150 which extends almost completely about an eccentric-like block 151, where its inner end is fixed to the block by suitable means such as screws 152. The block 151 is

of the contour shown in Fig. 1 and is mounted upon a shaft 153 which is journalled in suitable bearings (not shown) disposed in a sleeve 154 (Fig. 2), the latter being supported by arms 155 of a bracket 156 mounted upon the rear wall of the base 10. As illustrated in Fig. 2, the shaft 153 is of sufficient length to extend to a position near the center line of the apparatus, where a substantially semi-cylindrical element 158 is mounted thereon for rotation therewith. The element 158 has a strip 159 fixed thereto, as at 160 (Fig. 1), and extends inwardly to a point where it is fixed to a pin 161 (Fig. 2), the latter being rotatably supported in the end of an arm 162 supported by or made integral with the sleeve 155. Through this structure it will be apparent that during the return movement of the table and its associated mechanism the sleeve 155 is moved forwardly with the arm 162, the pin 161 and the strip 159, causing rotation of the element 158 and the shaft 153 a definite distance to cause expansion of the spring 144, through the block 151 and the strip 150, conditioning this means, including the creation of a desired force in the spring, to function in imparting a feeding motion to the table and the work when the proper time in the operating cycle of the apparatus arrives. The strips 150 and 159 may be of any suitable structure such as woven fabric, sheet metal or the like. During the rotation of the shaft 153 oscillatory movement is imparted to a plurality of switch arms 163, 164 and 165 to operate switches 166, 167 and 168 respectively, the function of these switches being hereinafter described.

Attention is now directed to Fig. 12, which illustrates a simple electrical circuit to control the motor 108 and the valve 135. Supply lines 170 and 171 lead into a magnetic switch 172, the operation of which is controlled through a manually operable switch 173. The valve 135 is operated through the energization of a coil 175 which is included in an electrical circuit when a relay 176 is energized to close a switch 177. The relay 176, however, is under the control of the limit switch 167 (Figs. 2 and 12). When the limit switch 167 is closed, through the actuation of its respective switch arm 165 (Figs. 1 and 12) a circuit is completed from the magnetic switch 172 through conductor 179, the switch 167, the relay 176, back to the switch 172, to conductor 180. The energization of the relay 176 will close the switch 177, completing a circuit through the coil 175 through connection with the conductors 179 and 180, respectively.

The motor 108 is electrically connected to the source of electrical energy, that is the leads 170 and 171, through the switch 172, by an electrical circuit which includes an electrically operated reversing switch indicated generally at 182, a thermo time delay relay 183 and an automatic time switch 184 in addition to the limit switches 168 and 166. The thermo time delay relay 183 is in the present instance of a commercially known type illustrated in a Catalog E, page 24E, entitled "Relays-Timers" published by Struthers Dunn Inc., Philadelphia, Pa. Furthermore, the automatic time switch is in the present instance of a commercially known type known as type TSA-10, illustrated on page 314 of Catalog GEA-620A entitled "Electrical Equipment for Industry" published by General Electric Company. The automatic time switch is electrically connected to the switch 172 through conductors 186 and 187, connected respectively to conductors 179 and 180. 75

Through this switch the time in which the motor 108 is energized is controlled. The length of time desirable for the energization of the motor depends upon the distance of movement of the table during each half of the cycle for the size of work or blank crystal being cut, and to cause the motor to function in conjunction with the table moving means which is under the control of the magnetic valve 135. The switch 182 is moved into the position shown by a relay 188 and into a reversing position by a relay 189. The relay 183 disposed in the reversing circuit controlled by the relay 189 causes the motor 108 to rotate in a reverse direction for a limited time to render the clutch 109 operable to cause operation of the table cross feed mechanism. The reversing of the motor is further controlled by the limit switch 166 through each switch arm 163. The limit switch 168 functions at a desired interval during the operation of the apparatus, to cause resetting of the automatic time switch 184.

Attention is now directed to Fig. 13, which illustrates the functioning of different features of the apparatus during each cycle of operation thereof beginning at the extreme left of this figure, which point may represent the beginning of the operating cycle. From this point the table starts its feeding movement by means of the spring 144. At a point shortly spaced therefrom, representing an interval of time, the motor 108 is energized to cause its rocking motion of the table 78. This continues throughout the feeding motion of the table, moving the work relative to the cutting element. At the center of the table 35 moving cycle, the limit switch 167 operates to open the valve 135 to admit air under pressure to the piston 130, causing return movement of the table. The piston 130 and the mechanism associated therewith act to limit the spring 144, stopping the feeding motion of the table and causing the return motion thereof. The motor 108 continues to oscillate the table during the return movement thereof excepting for a short distance near the end of such movement, indicated in Fig. 45, where the motor is stopped. At this point the limit switch 168 is operated to reset the automatic switch 184. At the completion of the return movement the limit switch 166 is closed to start the motor in reverse direction, causing the clutch 109 to function to operate the mechanism to bring about a cross feeding of the table to position the work for a new cut by the cutting element. This cross feed of the table is represented by a horizontal line connecting the end of the return movement with the point representing the beginning of the next operating cycle. At this point, that is, at the beginning of the next operating cycle, the valve 135 is closed to render inoperative the means for returning the table and for holding the table in the forward position, which in turn renders the spring 144 effective to start the feeding movement of the table. At this point the motor 108 is also stopped by the time delay relay, to condition the motor for starting in the opposite direction to again begin its oscillatory movement of the table. 55

With the diaphragm shown in Fig. 13 as a guide, the operation of the apparatus may be more clearly understood. Let it be assumed that the table 78 with its associated mechanism is in the forward position shown in Figs. 1 and 4, the table having been moved laterally for a new cut in the work. To start the table in its feeding direction the valve 135 is closed, rendering the hydraulic means associated therewith

inoperative to further move the table forwardly or to hold the table in its forward position and render the spring 144 effective to begin the feeding movement of the work toward the cutting element. The force of the spring 144 will create a pull on the strip 150 (Fig. 1), causing rotation of the shaft 153 through the association of the block 151, causing simultaneous rotation of the element 158, which in turn creates a rearward pull on the strip 159. The pull on the strip 159 is applied to the arm 162 (Figs. 2 and 4), causing rearward movement of the sleeve 55. The sleeve 55, through its shaft 54, causes counterclockwise movement of the pendulum levers 28 and, through the rocker arms, causes counterclockwise movement of the pendulum levers 40. These movements of the pendulum levers about their shafts 23 and 25 create an oscillatory movement which is imparted to the support 63 supported between the forward ends of the rocker arms 50. The combined motions of the pendulum levers results in the movement of the table 78, and the work mounted thereon, through an arc represented by the bottom of a cut 192 illustrated in Fig. 11. Therefore, the movement imparted to the table by the cooperation of the pendulum levers about their individual axes moves the work through the arc to cause the cutting element to leave an uncut portion beginning at an edge indicated at 193 (Fig. 11) and ending at an edge 194, the intermediate portion, however, increasing in thickness between these edges to a sufficient thickness adjacent the center to support the thin plate being cut from the blank during the complete cutting operation and until all of the cuts in the blank have been completed. In cutting work such as quartz crystal, it is important that unnecessary friction between the cutting element and the work be eliminated, to avoid burning. To avoid this difficulty while making a straight cut through a quartz crystal, where the periphery of the cutting element will engage the work for a considerable distance, it is necessary to reduce the speed of rotation of the cutting element and thus the resulting speed of operation of an apparatus, to eliminate a high degree of friction and burning. This difficulty is eliminated and the friction is reduced to a minimum by imparting an oscillatory or rocking movement to the table and thus to the work during the feeding operation. Such movement is imparted to the table and work through the motor 108, its eccentric 113, the link 114 and the bracket 116, which, during the energization of the motor, will oscillate the support 63 about its pivots, namely the stub shafts 60, rocking the table 78 and the work 84 to move the work from the position shown in Fig. 9, where the cutting element engages the work at substantially a point contact at the bottom of the cut, to a position, illustrated in Fig. 10, where the cutting element engages the work at substantially a point contact at the top of a cut. Similar point contacts are made between the cutting element and the work throughout the rocking or oscillatory movement of the work relative to the cutting element from the point illustrated in Fig. 9 to the point illustrated in Fig. 10. This oscillatory motion is continually imparted to the work throughout the feeding operation as well as the return movement excepting for the intervals of time during each portion of the operating cycle which exist at the beginning of the feeding movement and at the end of the return movement when the motor 108 is deenergized. During the feeding move-

ment of the table the spring 137 functions to cancel the weight component of the pendulum levers, to render the spring 144 effective to apply a constant force in moving the work toward the cutting element throughout the feeding movement.

The rotation of the shaft 153, through the force of the spring 144, imparts movement to the switch arms 163, 164 and 165 mounted thereon, these arms being adjustable to vary the time during the operating cycle of the apparatus for the actuation of their respective limit switches. At a selected time during the feeding movement of the apparatus, the limit switch 167 is closed, causing energization of the relay 176 to close the switch 177 (Fig. 12), resulting in the energization of the coil 175 to open the valve 135. When the valve 135 is opened air under pressure is admitted to the cylinder 131, forcing the piston 130 downwardly, which movement is controlled by the needle or pressure relief valve 136 at the bottom of the cylinder, to cause movement of the arm 128. The arm 128, as illustrated in Fig. 5, will be moved clockwise, imparting similar movement to the pendulum levers 40, and through the association of the rocker arms 50, impart clockwise movement to the pendulum levers 28. In this manner the table 78 with the work is moved from the position shown in Fig. 5 to the position shown in Fig. 4, returning the work to the starting position, moving the work in the same arcuate path that it travelled during its feeding movement. When the table has been returned to its starting position the valve 135 remains open to hold the spring 144 ineffective to move the table until the lateral adjustment of the table has been completed. The lateral adjustment of the table is brought about through the limit switch 166, reversing the motor 108 through the relay 189 and starting the operation of the thermo time delay relay 183. The motor 108 remains energized in this reverse direction under the control of the relay 183, causing a driving of the pinion 106 and the gear 105 in reverse directions also. This rotation of the rear 105 results in rendering the clutch 109 effective to operatively connect the gear 105 to the shaft 101, causing rotation of the telescoping shaft 98 to rotate the worm 89 (Figs. 2, 6 and 7). The rotation of the worm 89 causes rotation of the worm gear 88 and similar rotation of the adjusting screw 80. Through the rotation of the adjusting screw 80 a nut 79 (Fig. 8) is caused to travel laterally to the left (Fig. 2) a distance controlled by the relay 183 to move the work 84 laterally a distance desirable for the next cut. When this has been accomplished the relay 183 will close the circuit to the motor 108, deenergizing the motor and thus stopping lateral motion of the table. At this time the valve 135 is closed, rendering the spring 144 effective to again move the table through the feeding cycle of the operation of the apparatus.

Mention was made during the previous feeding cycle of the spring 137 cancelling the weight component of the pendulum levers to render the spring 144 effective to apply a constant force to the material throughout the feeding cycle. To more fully understand the function of the spring 144 and its connecting means with the table, attention is directed to the block 151 and its connection with the spring through the strap 150. The contour of the block 151 is such that, as the force of the spring 144 diminishes, during the feeding cycle, a lever arm, existing through the

strap 150 and the block, between the spring and the shaft 153 increases proportionately to the diminishing force of the spring to cause application of the constant force to operate the mechanism, associated with the shaft, to move the table. The length of the lever arm may be measured along a vertical line extending from the center of the shaft to the point where such line would intersect the strap beneath the shaft. To illustrate, if it were possible to further rotate the block clockwise and cause the straight portion of the strap 150 from the spring to intersect the axis of the shaft 153, the length of the lever arm would be nil. In such a position there would not exist sufficient force in the spring to rotate the shaft, as the connection thereof with the block would be on dead center with the shaft. As this connection moves further from the dead center position, the lever arm increases in length to its greatest length which exists when the extreme left of the lower or flat portion of the block is in a vertical plane with the axis of the shaft. Thus, from the position of the block shown in Fig. 1 to that just described, the lever arm increases in length proportionately to the diminishing force of the spring to translate the varying spring force into a constant force at the table. The spring 137 functions in the same manner during the return movement of the table, assisting the pneumatic means, namely the piston 130 and its associated parts, to apply a constant force in moving the table and the work to the starting position.

It will be understood that during the operation of the apparatus the motor 122 remains energized, causing continuous rotation of the cutting element, during which time a suitable lubricant may be applied thereto through the supply line 125.

Prior to the cutting of the crystal blank the blank is examined to determine the direction of the grain therein and the blank is marked to indicate the same. After the blank is mounted on the table, the table is adjusted to cause the direction of the grain of the work to be parallel with the cutting element. This adjustment may be brought about through the loosening of the wing nuts 73 (Fig. 1), loosening the bolts 70 (Fig. 14) to permit desired movement of the table supporting member 69 relative to the support 63 which is controlled by the arcuate ribs of the former, riding in the arcuate groove of the latter, and the similar movement of the bolts 70 to the desired position, after which the wing nuts 73 may be tightened to secure the table supporting member in the adjusted position on the support.

During the operation of the apparatus, it will be understood that two oscillatory movements are imparted to the table, one through the cooperating movements of the pendulum levers and their associated rocker arms to cause formation of the arcuate cut through the work, as illustrated in Fig. 11, the other oscillatory movement being repeatedly applied to the work to constantly shift the point of engagement of the work with the cutting element to cause the arc of the cut to be greater than the engaging arc of the cutting element, to result in substantially point contact between the cutting element and the work. Furthermore, the moving means to move the table relative to the cutting element is not only variable through the adjustment of the nuts on the rods 145 and 147 for varying the force of the spring 144 and the adjustment of the valves associated with the cylinder for varying the effec-

tive force of the piston 130, but each force, whether it be the pneumatic means or the spring forcing means, is of the nature of a cushioned force applied to the work.

5 The embodiment of the invention herein disclosed is merely illustrative and may be modified and departed from in various ways without departing from the spirit and scope of the invention as pointed out in and limited only by the 10 appended claims.

What is claimed is:

1. In a cutting apparatus, a rotary cutting element, a table to support work to be cut by the element, an operable mechanism connected to the table, a spring having a given starting force diminishing when utilized to actuate the mechanism, and means operatively connecting the spring to the mechanism and adapted to convert the diminishing force received thereby from the spring into a constant force transmitted thereby to the mechanism to cause operation of the mechanism to move the table in a direction to feed the work to the element under a constant force to cause the element to cut through the work.

15 2. In a cutting apparatus, a rotary cutting element, a table to support work to be cut by the element, an operable mechanism connected to the table, a spring having a given starting force diminishing when utilized to actuate the mechanism, means operatively connecting the spring to the mechanism and adapted to convert the diminishing force received thereby from the spring into a constant force transmitted thereby to the mechanism to cause operation of the mechanism to move the table in a direction to feed the work to the element under a constant force to cause the element to cut through the work, and means to cause operation of the mechanism and connecting means to move the table in the opposite direction and to restore the given force in the spring.

3. In a cutting apparatus, a rotary cutting element, a table to support work to be cut by the element, an operable mechanism connected to the table, a spring having a given starting force diminishing when utilized to actuate the mechanism, and a movable member operatively connecting the spring to the mechanism and having an effective lever arm which increases proportionately to the diminishing force of the spring to cause application of a constant force to operate the mechanism to move the table in a direction to feed the work to the element under a constant force to cause the element to cut through the work.

4. In a cutting apparatus, a rotary cutting element, a table to support work to be cut by the element, an operable mechanism connected to the table, a spring having a given starting force diminishing when utilized to actuate the mechanism, a movable member operatively connecting the spring to the mechanism and having an effective lever arm which increases proportionately to the diminishing force of the spring to cause application of a constant force to operate the mechanism to move the table in a direction to feed the work to the element under a constant force to cause the element to cut through the work, and means to cause operation of the mechanism and movable member to move the table in a reverse direction and to restore the given force in the spring.

DANIEL V. WATERS.
